Official Report of the Board of Audit and Audit Office

United States Patent Office.

RICHARD SMITH, OF PHILADELPHIA, PENNSYLVANIA, ASSIGNOR TO MAC-KELLAR, SMITHS & JORDAN, OF SAME PLACE.

Design No. 4,213, dated July 5, 1870.

DESIGN FOR TYPE.

The Schedule referred to in these Letters Patent and making part of the same.

I, RICHARD SMITH, of Philadelphia, in the county of Philadelphia and State of Pennsylvania, (assignor to MAC-KELLAR, SMITHS & JORDAN,) have invented and produced a new and original Design for Printing-Type, of which the following is a specification.

The nature of my design is fully represented in the accompanying impressions, to which reference is made, in which impressions both the capitals and lower-case letters are shown made in accordance with my design, which design is preserved in any signs, symbols, or numerals that may be required.

I claim as my invention—

The design for printing-type, as shown.

RICHARD SMITH.
